CLAIM

The ornamental design for a beach umbrella, as shown and described.

DESCRIPTION

FIG. 1 is a top perspective view of a beach umbrella, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a bottom perspective view of the tilting state thereof;

FIG. 10 is an enlarged detail view of area 10 in FIG. 2 thereof;

FIG. 11 is an enlarged detail view of area 11 in FIG. 2 thereof;

FIG. 12 is an enlarged detail view of area 12 in FIG. 2 thereof; and,

FIG. 13 is an enlarged detail view of area 13 in FIG. 9.

The broken lines in the drawings illustrate the portions of the beach umbrella, which form no part of the claimed design. The dash-dot-dash broken lines encircling the enlarged views are for annotative purposes only and form no part of the claim thereof.
